(57) **CLAIM**

The ornamental design for a fluid output connector, as shown and described.

DESCRIPTION

FIG. 1 is a top, front, right side perspective view of a fluid output connector, showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom, rear, left side perspective view thereof. Features shown in broken lines in the drawings form no part of the claimed design.

The surfaces that sit between an exterior edge shown in evenly spaced broken lines and an interior edge shown in solid lines of the top face of the article in FIGS. 1 and 6 are not part of the claimed design.
